CHLOROPHENOTHIAZINECARBOXAMIDES

John W. Cusic, Skokie, and Markus Zimmermann, Evans-ton, Ill., assignors, by mesne assignments, to G. D. Searle & Co., Skokie, Ill., a corporation of Delaware

No Drawing. Application February 14, 1955,
Serial No. 488,110

9 Claims. (Cl. 260—243)

This invention is concerned with a new group of chlorophenothiazinecarboxamides and, more particularly, with the compounds of the basic structural formula

and the non-toxic salts thereof, wherein X is a halogen atom and preferably chlorine or fluorine, Alk is a lower alkylene radical separating the two nitrogen atoms attached thereto by at least two carbon atoms and NR'R'' is a member of the class consisting of dialkylamino and nitrogen containing heterocyclic radicals which are attached to the group Alk through a nitrogen in the heterocycle.

In the foregoing structural formula the radical Alk represents a bivalent, saturated, aliphatic hydrocarbon radical derived from a straight or branched-chain hydrocarbon and which includes radicals such as ethylene, propylene, butylene, amylene, hexylene and polymethylene radicals such as trimethylene, tetramethylene, pentamethylene, and hexamethylene. The radicals R' and R'' can represent such lower alkyl radicals as methyl, ethyl, straight and branched propyl, butyl, amyl, and hexyl radicals. The radical NR'R'' can also represent a nitrogen-containing radical such as a piperazino, N'-(lower alkyl)piperazino, thiamorpholino, tetrahydroquinolino, and tetrahydroisoquinolino radical, but of special value for the purposes of this invention are heterocyclic radicals in which NR'R'' represents pyrrolidino, piperidino, and morpholino radicals.

The organic bases of the foregoing type form pharmaceutically acceptable non-toxic salts with a variety of inorganic and strong organic acids including sulfuric, phosphoric, hydrochloric, hydrobromic, sulfamic, citric, ascorbic, and related acids. They also form quaternary ammonium salts with a variety of organic esters of sulfuric, hydrohalic and aromatic sulfonic acids. Among such esters are methyl chloride and bromide, ethyl chloride, propyl chloride, butyl chloride, isobutyl chloride, benzyl chloride and bromide, phenethyl bromide, naphthyl chloride, dimethyl sulfate, diethyl sulfate, methyl benzene-sulfonate, ethyl toluenesulfonate, ethylene chlorohydrin, propylene chlorohydrin, allyl bromide, methallyl bromide, and crotyl bromide.

In U. S. Patent No. 2,627,517, issued February 3, 1953, one of us (John W. Cusic) described certain non-halogenated basically substituted phenothiazinecarboxamides. It has now been found that by substitution of a halogen atom in the phenothiazine moiety of these amides there are obtained medicinally valuable products with a pharmacological spectrum of activities different from that shown by the non-halogenated phenothiazinecarboxamides. Specifically, the compounds of this invention have a strong anti-emetic effect, a tranquilizing effect in cases of hyperirritability and of over-stimulation of the

2

central nervous system. Their effect is directed specifically to the central nervous system and they do not share the activity of the previously described non-halogenated phenothiazinecarboxamides on the sympathetic nervous system. As an example, they fail to show the potent inhibiting effect of the action of acetylcholine on the intestine exhibited by the compounds of U. S. Patent No. 2,627,517.

The invention will be described more fully in conjunction with the following examples. However, it should be understood that these examples are given by way of illustration only and that the invention is not to be construed as limited in spirit or in scope by the details set forth. In these examples temperatures are given uncorrected in degrees centigrade and quantities of materials in parts by weight.

Example 1

To a mixture of 60 parts of 2-chlorophenothiazine in 500 parts of toluene and 40 parts of phosgene in 100 parts 20 of toluene, there are added gradually 32 parts of pyridine. After stirring at room temperature for 90 minutes, the temperature is slowly raised to 80° C. When the mixture has regained room temperature, 20 parts of phosgene in 50 parts of toluene are added and then, gradually, 16 parts of pyridine. The mixture is maintained at room temperature for 2 hours, after which it is gradually heated to 110° C. and maintained at that temperature for 2 hours. The mixture is then poured into ice water. The organic layer is washed repeatedly with water and then dried over calcium chloride and concentrated under vacuum to a total of about 525 parts.

To this solution of 2-chloro-10-chloroformylphenothiazine there are added 37 parts of N,N-dimethylmethylenediamine and the reaction mixture is refluxed for 2 hours. 35 It is then cooled and extracted with dilute hydrochloric acid. This extract is rendered alkaline by addition of cold aqueous sodium hydroxide solution and extracted with ether. The ether extract is dried over anhydrous sodium sulfate, filtered and evaporated. On repeated recrystallization from ethanol and benzene and then from ethanol and ether, the N-(β-dimethylaminoethyl)-2-chloro-10-phenothiazinecarboxamide is obtained in very fine colorless needles.

Treatment of an ether solution of this base with 1 molecular equivalent of hydrogen chloride in propanol causes precipitation of a hydrochloride which, recrystallized from a mixture of ethyl acetate and ethanol using charcoal clarification melts at about 200–201° C. This salt has the structural formula

Example 2

To a solution of 56 parts of 2-chloro-10-chloroformylphenothiazine in 900 parts of toluene are added 41 parts of N,N-dimethyltrimethylenediamine and the mixture is refluxed for 2 hours. It is then cooled and extracted with dilute hydrochloric acid. The extract is rendered alkaline with dilute sodium hydroxide solution and the base is extracted with ether. This ether extract is dried over anhydrous calcium sulfate, filtered and evaporated. The residue is taken up in ether and treated with one equivalent of a 25% solution of hydrogen chloride in 2-propanol. The precipitated hydrochloride is taken up 65 in ethanol and reprecipitated by addition of ethyl acetate. Repeated recrystallization from a mixture of ethanol and ethyl acetate using charcoal decolorization yields N-(γ-

3

dimethylaminopropyl) - 2 - chloro - 10 - phenothiazinecarboxamide hydrochloride melting at 176-177° C.

Example 3

A mixture of 56 parts of 2-chloro-10-chloroformylphenothiazine and 46 parts of N,N-diethylethylenediamine in 800 parts of butanone is refluxed for 2 hours, concentrated to one-fifth of its original volume, diluted with ether and extracted with dilute hydrochloric acid. This acid extract is rendered alkaline by addition of dilute sodium hydroxide solution and extracted with ether. The ether solution is dried over anhydrous sodium sulfate, filtered and evaporated. The residue is dissolved in dry ethanol and one equivalent of hydrogen chloride in propanol is added. On concentration of the resulting mixture the hydrochloride separates as an oil. Repeated crystallization from acetone and a small amount of ethanol yields the hydrochloride of N-diethylaminoethyl-2-chloro-10-phenothiazinecarboxamide melting at about 200-201° C.

Example 4

To a solution of 11.9 parts of 2-chloro-10-chloroformylphenothiazine in 120 parts of butanone are added 10.4 parts of N,N-diethyltrimethylenediamine and the mixture is heated at reflux for 2 hours. It is then poured into ice water and the aqueous solution is washed with ether, rendered alkaline by addition of sodium hydroxide and extracted with ether. The ether extract is dried over anhydrous sodium sulfate, filtered and evaporated. The residue, containing the N-(γ -diethylaminopropyl)-2-chloro-10-phenothiazinecarboxamide, is taken up in ether and treated with one equivalent of hydrogen chloride in propanol. Recrystallized repeatedly from a mixture of alcohol and acetone using charcoal clarification, the hydrochloride melts at about 184-185° C.

Example 5

A mixture of 63.5 parts of 2-chloro-10-chloroformylphenothiazine and 55 parts of N-(β -aminoethyl)-piperidine in 450 parts of toluene is refluxed for 1 hour and then cooled and treated with dilute aqueous hydrochloric acid. The aqueous layer is separated, rendered alkaline by addition of dilute potassium hydroxide and extracted with ether. This extract is dried over anhydrous potassium carbonate, filtered and evaporated to yield as a residue N-(β -piperidinoethyl)-2-chloro-10-phenothiazinecarboxamide. Treatment of an ether solution of this base with 1 equivalent of a 25% solution of hydrogen chloride in 2-propanol yields a crystalline hydrochloride which, recrystallized from butanone, melts at about 188-190° C. The compound has the structural formula

Example 6

A solution of 127 parts of 3-chloro-10-chloroformylphenothiazine and 110 parts of N-(β -aminopropyl)-pyrrolidine in 2000 parts of butanone is refluxed for 3 hours, concentrated to about 400 parts, diluted with ether and treated with aqueous hydrochloric acid. The aqueous layer is separated, washed with ether, rendered alkaline by the addition of dilute sodium hydroxide solution and then extracted with ether. This extract is dried over anhydrous calcium sulfate, filtered and evaporated to yield

75

the yellowish oily N-(β -pyrrolidinopropyl)-3-chloro-10-phenothiazinecarboxamide. It has the structural formula

Example 7

A solution of 78 parts of 2-chloro-10-chloroformylphenothiazine and 33.4 parts of N-(β -aminoethyl)morpholine in 400 parts of butanone is refluxed for an hour and then poured into ice water. The aqueous solution is washed with ether, rendered alkaline with sodium carbonate, and then extracted with ether. This extract is dried over anhydrous potassium carbonate, filtered, treated with one equivalent of gaseous hydrogen chloride in 2-propanol, and evaporated. The residue is dissolved in ethanol, clarified with charcoal and then treated with ethyl acetate and concentrated to yield the hydrochloride of N-(β -morpholinoethyl)-2-chloro-10-phenothiazinecarboxamide melting at about 192-193° C. The compound has the structural formula

Example 8

35

13 parts of N-phenyl-4-fluoroanthranilic acid are heated to about 270° C. for 90 minutes and then dissolved in ether. The ether solution is washed with 2-N sodium hydroxide and with water and then dried over anhydrous sodium sulfate. After evaporation of the ether the residue is distilled at about 0.05 mm. pressure and 70° C. to yield m-fluorodiphenylamine as a colorless oil. A mixture of 3.7 parts of this oil, 1.3 parts of sulfur and 0.1 part of iodine are heated at 180-195° C. for an hour. The residue is sublimed in vacuum and then crystallized repeatedly from ethanol to yield 2-fluorophenothiazine melting at about 200-201° C.

40

Reaction of this compound with phosgene in toluene by the method of Example 1 yields a toluene solution of 2-fluoro-10-chloroformylphenothiazine. A solution of 53 parts of this compound and 69 parts of N-(δ -aminobutyl)-diisopropylamine in 1000 parts of toluene is refluxed for 2 hours. It is then cooled and treated with dilute hydrochloric acid. The aqueous layer is separated, rendered 45 alkaline with dilute sodium hydroxide and extracted with ether. This ether extract is dried over anhydrous sodium sulfate, filtered and evaporated to yield as a residue N-(δ -diisopropylaminobutyl)-2-fluoro-10-phenothiazinecarboxamide in the form of a yellow resin.

60

Example 9

55

By the procedure of the foregoing example 3-fluorophenothiazine is prepared which melts at about 176-177° C. Substitution of 58 parts of this compound for the 2-chlorophenothiazine used in Example 1 yields the N-(β -dimethylaminopropyl)-3-fluoro-10-phenothiazinecarboxamide in the form of a light orange resin. What is claimed is:

70

1. A compound of the structural formula

wherein X is a halogen atom of an atomic weight less than 40, Alk is a lower alkylene radical separating the two nitrogen atoms attached thereto by at least two carbon atoms and NR'R'' is a member of the class consisting of di-(lower)alkylamino, pyrrolidino, piperidino and morpholino radicals.

2. A compound of the structural formula

wherein Alk is a lower alkylene radical separating the two nitrogen atoms attached thereto by at least two carbon atoms.

3. A compound of the structural formula

4. A compound of the structural formula

5. A compound of the structural formula

6. A compound of the structural formula

wherein Alk is a lower alkylene radical separating the two nitrogen atoms attached thereto by at least two carbon atoms and n is a positive integer less than 3.

7. A compound of the structural formula

8. A compound of the structural formula

wherein Alk is a lower alkylene radical separating the two nitrogen atoms attached thereto by at least two carbon atoms.

9. A compound of the structural formula
